[57] CLAIM

The ornamental design for a record hanger plaque, as shown and described.

DESCRIPTION

FIG. 1 is a front elevational view of a record hanger plaque showing my new design;

FIG. 2 is the right side elevational view thereof;

FIG. 3 is a rear elevational view thereof;

FIG. 4 is a top plan view thereof;

FIG. 5 is a bottom plan view thereof.
